Primary Examiner — Bao-Yen T Nguyen*Assistant Examiner* — Emily Anna Saunders(74) *Attorney, Agent, or Firm* — Jose Cherson Weissbrot(57) **CLAIM**

The ornamental design for a bubble machine as shown and described.

DESCRIPTION

FIG. 1 is a front, top perspective view of the bubble machine, showing my new design;

FIG. 2 is a rear, bottom perspective view thereof;

FIG. 3 is a front elevational view thereof;

FIG. 4 is a rear elevational view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of the area labeled 9 in FIG. 1;

FIG. 10 is an enlarged view of the area labeled 10 in FIG. 1; and,

FIG. 11 is an enlarged view of the area labeled 11 in FIG. 1. The broken lines in the figures are for the purposes of illustrating portions of the bubble machine, which form no part of the claimed design. The dot-dash broken lines encircling portions of the bubble machine in FIG. 1 and illustrated in enlarged views in FIGS. 9, 10 and 11 form no part of the claimed design.

1 Claim, 11 Drawing Sheets(56)
